UNITED STATES PATENT OFFICE

2,443,508

ELECTRIC TIMING APPARATUS

Edwin W. Landmeier, Lakeside Park, Ky., assignor to The Wadsworth Electric Manufacturing Co., Inc., Covington, Ky., a corporation of Kentucky

Application March 5, 1945, Serial No. 581,107

5 Claims. (Cl. 200—39)

1

This invention relates to a timing mechanism, and is directed particularly to a continuously operating timer which may be set to close a switch at a given moment and to open the switch at the expiration of a predetermined interval of time. The invention is disclosed in the form of an apparatus operable throughout a twenty-four hour cycle for opening and closing the switch which it controls at given hours of the day; for instance, the apparatus finds usage as a controller for electric lights or a sign in a store or building, being set to turn on the lights at dusk and turn them off at dawn. Other uses, and timing cycles other than the twenty-four hour cycle, which is selected as a representative one, may be employed as required by the conditions to be controlled.

The principal purpose of this invention has been to provide a simplified structure which is inexpensive to construct and which may be fabricated conveniently from a minimum number of sheet metal parts. The unit is adapted to be driven electrically from a synchronous motor of negligible current consumption and employs reduction gears which, subjected to only light mechanical loads, suffer little wear during continued usage.

Another objective has been to provide an electric timer mechanism having at least a pair of switch contacts movable longitudinally toward and from one another for switch opening and closing, and also having limited relative movement in a lateral direction. One or both of the cooperating contacts present laterally inclined or crowned meeting faces such that, as they are brought into engagement, a wiping movement occurs at the inner face which cleanses the contact surfaces and thereby maintains them in an efficient conductive condition. This arrangement is employed in order that the timer will continue to give reliable service even though its contacts are exposed to unfavorable weather conditions or to current of such density that switches of the usual construction would soon fail because of pitting, surface oxidation or corrosion.

In the preferred construction of the apparatus, a time cycle dial is employed having thereon a pair of controller elements which operate therewith and which are adjustable so that they may be set to the time when the switch is to be opened and closed. The switch contacts are biased toward one another, both are movable longitudinally and one of the contacts is latched in an open position through a pawl actuated from the timer dial, whereby it approaches the other for switch closure when released by the pawl. The second

2

of the contacts is operated from a cam engaged by the other control element of the timer dial in such manner that it is moved toward the first; thereafter it moves the first to its latched position and finally is itself released, whereupon it withdraws to open the switch. This construction provides a "snap action" effect in causing the contacts to make and break engagement very suddenly to minimize arcing.

10 The invention contemplates switches of both the single and double pole variety, the releasing pawl which controls switch closure being common to both switches of a double pole pair while a pair of levers, toggle connected and operable in unison, serves the pair of switches to control switch opening.

From the foregoing discussion of the salient features of the improvement and from the following detailed description of the drawings in which a preferred embodiment of the invention is illustrated, those skilled in the art readily will comprehend the various modifications to which the invention is susceptible.

In the drawings:

25 Figure 1 is a front elevation of the timer.
Figure 2 is a rear elevation.

Figure 3 is a view similar to Figure 2 showing the switches in closed position.

Figure 4 is a cross sectional view taken on the 30 line 4—4 of Figure 1.

Figures 5, 6 and 7 are diagrammatic views, Figure 5 showing the relationship of the parts when the switches are about to close; Figure 6 showing the relationship of the parts as the 35 switches are about to be conditioned for opening; and Figure 7 showing the switches conditioned to open and on the verge of opening.

Figure 8 is a cross sectional view taken on the line 8—8 of Figure 3.

40 The device shown in the drawings is assembled upon a frame indicated generally at 1 comprising a lower vertical portion 2, an offset upper vertical portion 3, and a cross connecting portion 4 which interconnects the two. The lower portion 2 of the frame has a clearance aperture 5 therein and, to one side, carries an insulation panel 6 which is fastened in place by means of the rivets 7. The panel carries a ground terminal 8, input terminals 9—9 through which current is supplied to the timer switch and output terminals 10—10 which are adapted for interconnection with the circuit that the switch is to control. At points behind the insulation panel 6 the lower portion 2 of the frame has terminal clearance apertures 11. Terminals 8, 9 and 10

45

50

55

are of usual construction comprising screws 12 carrying connectors 13 which are locked in place by means of the nuts 14. The heads of the screws 12 bear against terminal connectors 15 which are in interconnection with circuit wires of the apparatus as described at a later point in the specification.

At the upper vertical portion 3 of the frame, a drive motor 16 is positioned, preferably at the front face of the panel where it is bolted in place by means of screws 17. The motor has a terminal block 18 extending through the platform 4 and the motor shaft passes through the plate 3 to the rearward face thereof where it carries a sprocket 20.

A bracket 21, having a foot fastened to the platform 4 of the frame, extends upwardly in spaced relationship to the frame back wall 3 and both, at their upper portions, are bored in alignment to support a hollow sleeve 22 which extends forwardly beyond the face of the bracket 21. A second hollow sleeve 23 is rotatably sustained within the sleeve 22 and it, in turn, rotatably supports a shaft 24. The middle sleeve 23 of this series has a setting dial 25 fastened to its forward end and a gear 26 fastened to its back end at a point adjacent the outer face of the rear wall 3.

Any suitable gear train or speed reduction movement may be interposed between the pinion 20 of the drive motor and the gear 26 which drives the setting dial. In the construction shown in the drawings motor pinion 20 is in mesh with a gear 27 having a smaller pinion 28 rigidly associated therewith, this couplet being mounted for rotation upon a shaft which is supported between the frame wall 3 and bracket 21. Pinion 28 drives a large gear 29 which is supported upon the inner shaft 24 of the spindle assembly, and gear 29 has rigidly associated with it a pinion 30 which is in mesh with a larger gear of another couplet 31—32, the smaller member of this couplet being in connection with the spindle gear 26 through which the dial is rotated.

The setting dial 25 has notches 33 at its periphery with adjacent indicia, indicated by the circles 34, denoting time positions. A pair of arms 35 and 36 respectively are rotatably supported upon the outer barrel 22 of the spindle assembly. Each of the arms 35, 36 has an ear or detent 37 extending laterally from its face for selective engagement in the notches at the dial periphery. The arms are yieldable and are independently movable with respect to one another such that they may be sprung from the dial face to disengage their detents from the notches, then rotated and set to any given time position. The arms have drive fingers or lugs 38 and 39, respectively, which extend laterally therefrom in opposite directions. Arm 36 and its finger 39 governs switch closure and arm 35, with its finger 38, governs switch opening.

As best illustrated in Figure 4, the setting dial 25 is preferably in two sections with the outer section 25a carrying a knob 40 fixed thereto. The inner shaft 24 of the spindle assembly extends through the dial assembly and the knob and has a head 41 at its outer end which forms a seat for one end of a compression spring 42 which is housed in a suitable recess in the knob for the purpose of holding the outer dial portion 25a in contact with the portion 25. The shaft head 41 is spaced a distance from the outer face of the knob 40 to allow it and the dial portion 25a to be pulled laterally from the dial section 25 to clear

the arm lugs 37. The dial section 25a can, therefore, be adjusted to correspond to the correct hour of the day.

In the double pole switch construction shown in the drawings two pairs of contact carriers are employed comprising upper slidable members 43, one for each pair, and respectively cooperating lower slidable members 44. These carriers are generally of block formation, made of insulating material, and ride within slots 45 provided in the plate 2 of the frame. As shown in Figure 8 each carrier has longitudinal flanges 46 extending outwardly therefrom intermediate its front and rear faces for engagement with the face of the plate 2, while the narrower portions of the blocks at one side of the flanges extend through the slots to carry metal bridges 47. The metal bridges are held to the carriers through screws 48 and the bridges, engaging the face of plate 2 at the side thereof opposite the longitudinal carrier flanges, slidably sustain the carriers on the plate.

The cooperating endwise portions of the contact carriers have contacts 49 thereon which are mounted upon angle pieces 50. These angles overlie the ends of the carrier blocks and extend along the faces thereof where they are fastened in place by means of screws 51, having washers associated therewith to provide terminals for the electrical connections to the switch contacts. All of the contact carriers are biased in an upward direction by means of springs 52, one spring for each carrier. The springs for the upper set have one end thereof caught on a hook 53 provided at the ledge 4 of the frame and the opposite end thereof caught on an ear 55 struck laterally from the bridge plate 47. The springs for the lower set of carriers have one end thereof caught on an ear 55 struck laterally from the bridge plate 47, as just described, while the upper end is connected to an ear bent laterally from the plate 2 at an edge of the central recess 5 therein.

The contact carrier blocks are movable in their slots, but it also is to be noted that the slots are sufficiently wide to permit the carrier blocks to shift sidewise or laterally. Contacts 49 of each cooperating pair are relatively inclined or crowned at their meeting faces whereby longitudinal movement of the contacts as they are brought into engagement with one another is accompanied by a lateral or sidewise movement. This sidewise movement exerts a wiping action by each contact 49 upon the face of its cooperating member and the surfaces of the contacts thus are abraded so as to maintain themselves in a clean and conductive condition. In other words, as the carriers move into engagement with one another under spring pressure, they become canted or shifted in their slots and the attendant abrading action helps to keep the contact surfaces in an efficiently operating condition even though they may be exposed to adverse atmospheric conditions.

For the purpose of opening and closing the contacts in accordance with the movement of the dial 25, the arms 35 and 36 which are driven thereby, respectively operate a switch closing lever 56 and a switch opening lever 57 or a pair of them as in the double pole construction shown. Switch closing lever 56 is an elongated piece which has a pivot or hub 58 riveted thereto intermediate its ends. This hub extends beyond the plane of the lever and has a counterclockwise portion 59 which is received within a sleeve 60 fastened rigidly to the plate 2. The hub of the

lever is threaded to receive a screw 61 which holds it in place. The upper portion of the lever 56 extends through a suitable clearance opening in the platform 4 of the frame to a point where it is engageable by finger 39 of the switch closing control arm 38. Lever 56 is biased in a direction against the rotation of the dial by means of a spring 62. When the spring is released the extremity of the lever lies in the path of movement of the actuating finger 39. During dial rotation the finger engages the lever and carries the lever with it against spring tension until pivotal rotation of the lever causes it to escape the finger.

The lower portion of the lever 56 spans the marginal portions of the lower contact carriers, and each of the plates 47 carried thereon has an ear 63 bent outwardly therefrom. These ears rest against the lower edge of the lever 56 when the switch is latched in open position. However, as the lever is swung, ear 63 on one of the blocks clears the longitudinal edge of the lever. To provide for a similar release of the other contact carrier the lower edge of the lever 56 has a recess 64 therein into which the ear 63 on the other contact carrier may move. Pivotal swinging movement of the lever 56 under the influence of the spring 62 is limited by a finger 66 extending from the plate 2 which resides in a slot 65, or in other suitable manner.

The function of the lever 56 to latch the lower contact blocks in switch open position is illustrated in Figure 5 in which it may be seen that the ears 63 rest upon the outer extremity of the lever. As the lever is swung in a clockwise direction (Figure 6) these ears are cleared and the contact carriers are permitted to spring upwardly to switch closed position.

Levers 57, through which the switch is opened, straddle the upper set of contact carriers and are pivoted to the plate 2 through the rivets or screws 68. Each of the levers 57 (for a single pole switch there is only one of them) has a finger 69 positioned for engagement with the upper end of an upper contact carrier, preferably that carrier which is remote from its pivot point. The levers in a pair are interconnected for movement in unison with one another through a pin 70 extending from one of them through a clearance slot 71 in the other. Thus, pivotal movement of either of the levers 57 will cause both upper contact carriers to be operated.

One of the levers 57 of the pair presents a cam surface 72 for engagement with switch opening finger 38 of the time dial (Figure 1). This cam is of such configuration that as it is engaged by the time dial finger 38 during rotation thereof, the levers 57 are depressed to cause downward movement of all of the contacts a distance sufficient to drive the ears 63 of the lower contacts past the lower extremity of the lever 56 before the finger 38 reaches the end of the cam. As soon as the ears 63 clear the lower portion of the lever 56 that lever is released to respond to the influence of the spring 62 and swing to a latched position with its longitudinal clearance edges out of alignment with the ears. This action occurs before finger 38 has reached the end of the cam 72. Thereafter the finger 38 leaves the end of cam 72, the levers 57 are released and the upper contacts spring upwardly under the influence of springs 52. However, at this moment the lower contacts are held in a latched and retracted position and the upper

contacts thus depart from them to open the switch.

Further rotation of the dial next brings the closing finger 39 into engagement with the extremity of lever 56, swinging it to move the longitudinal clearance edges thereof past the ears 63 thereby releasing the lower contacts so that they are free to move into engagement with the upper contacts for switch closure. In each of these movements it is to be noted that engagement and disengagement of the electrical contacts is very sudden; there is no gradual approach and departure of the contacts toward and from one another whereby arcing could occur through incomplete engagement. Moreover, under spring action the impact of the contacts with one another augments the abrading action which is provided through the lateral shiftability of the contact carriers.

Springs 52, activating the upper set of contacts, extend outwardly from one another, or in an angle with respect to the longitudinal path of the contact movement and their effect upon the contacts is to pull the contacts sidewise toward the outer edges respectively of the guide slots within which they ride. The same construction preferably also is employed in the construction of the lower set of contacts. This arrangement, relative to the slope of the contact surfaces, disposes them in shiftable positions when they engage one another and precludes the contacts from occupying relatively shifted positions prior to their engagement.

While the invention has been disclosed in relation to a structure in which both the upper and the lower contacts of a pair are shiftable, it is to be understood that the invention contemplates arrangements wherein one of the contacts is stationary or unshiftable since it is the relative lateral movement that provides the desired cleansing action.

In the electrical circuit disclosed in the drawings input terminals 9 are interconnected with the lower contacts through leads 74 and 75 respectively; leads 76 and 77 also are taken therefrom to the motor terminals, while the upper contacts are connected with the output terminals through leads 78 and 79.

By virtue of the adjustability of the control fingers 38 and 39 upon the time dial they may be spaced apart from one another at various positions about the entire periphery of the time dial to control switch closing and switch opening at any given time throughout the cycle of rotation. Moreover, while the contacts move as they are being conditioned to open, still this movement does not affect the moment when the contacts separate, nor impair the accuracy of the adjustment. It will be seen that for this reason the levers 56 and 57 need not be made to precise dimensions and can be fabricated inexpensively from simple sheet metal parts.

Having described my invention, I claim:

1. An electric circuit controller comprising a rotatable member, an electric power drive for rotating said member at a fixed speed, said rotatable member having switch opening and switch closing actuating elements adjustably associated therewith, a latch operated by one of said elements, a lever operated by the other of said elements, and a pair of contacts biased against lever movement and movable by said lever in unison for moving one of the contacts to a position where it is engaged and held in a switch open position by said latch and for thereafter releasing the

other of said contacts, one of the contacts of the pair being shiftable in a direction lateral to the path of movement through which it is operated by said lever; and at least one of said contacts presenting to the other a face of angular configuration for effecting lateral displacement of the laterally moved contact whereby each of the contacts exerts a wiping action upon the face of the other.

2. An electric circuit controller comprising a rotatable member, an electric power drive for rotating said member, said rotatable member having switch opening and switch closing actuating elements adjustably associated therewith, a latch operated by one of said elements, a lever operated by the other of said elements, a pair of slidable contacts, said switch opening lever being arranged to move said contacts in unison whereby one of said contacts is engaged and held in a switch open position by said latch, one of said contacts of the pair being loosely shiftable in a direction lateral to the path of movement through which it is operated by said lever, one of the contacts of the pair presenting to the other a face of generally angular configuration, whereby relative lateral displacement between the contacts is effected upon their engagement under pressure, and biasing means for providing displacement pressure coincidental with engagement of the contacts.

3. An electric circuit controller comprising a rotatable member, an electric power drive for rotating said member, said rotatable member having switch opening and switch closing actuating elements adjustably associated therewith, a latch operated by one of said elements, a lever operated by the other of said elements, a pair of contacts slidable by said lever in unison for moving one of the contacts to a position where it is engaged and held in a switch open position by said latch, one of said contacts of the pair being loosely shiftable in a direction lateral to the path of movement through which it is operated by said lever, one of the contacts of the pair presenting to the other a face of generally angular configuration, whereby relatively lateral displacement between the contacts is effected upon their

engagement under pressure, and biasing means for providing displacement pressure coincidental with engagement of the contacts, said biasing means comprising a spring urging the laterally displaceable one of said contacts in a direction opposite the direction in which it moves during displacement.

4. An electric circuit controlling device comprising; at least two pairs of contacts, all slidable upon substantially parallel axes, a latch common to one contact of each pair for holding said contact in switch-open position, means including the second contact of each pair for driving the first contact of each pair to latching position, said means also including levers, one for each pair of contacts in engagement with the second contact thereof and being movable in unison, and a timing mechanism for actuating said levers and for actuating said latch.

5. An electric circuit controller comprising; at least two pairs of contacts arranged in side by side relationship and all slidable, means for biasing all of the contacts in one direction, a pair of levers movable in unison straddling the pairs of contacts and the said levers respectively engaging one contact of each pair for moving the contacts in an opposite direction, a latch common to the other contact of each pair for holding the said other contacts in switch-open positions against said biasing means, means including said levers for driving all contacts toward latching position for engagement of the second contact of each pair by said latch, means for abruptly releasing the said levers to permit the first contact of each pair to recede from the second contact of each pair, and means for releasing said latch.
